UNITED STATES PATENT OFFICE.

FREDERICK HERMANN JURY, OF NEW YORK, N. Y.

WINDOW.

SPECIFICATION forming part of Letters Patent No. 424,306, dated March 25, 1890.

Application filed April 2, 1889. Renewed March 5, 1890. Serial No. 342,804. (No model.)

To all whom it may concern:

Be it known that I, FREDERICK HERMANN JURY, a citizen of New York, in the county of New York and State of New York, have 5 invented certain new and useful Improvements in Windows; and I do hereby declare the following to be a full, clear, and exact description of the invention, such as will enable others skilled in the art to which it appertains 10 to make and use the same.

My invention relates to an improvement in windows, and more particularly to carriage and car windows.

Prior to my present invention various contrivances have been devised for preventing the sticking of windows and to provide the windows with devices whereby they may be easily manipulated; but such prior devices, so far as I am aware, have not performed the 20 result for which they were intended to the desired extent.

Car and carriage windows are frequently mounted to slide loosely, and it has also been the aim of prior constructions to prevent 25 such windows from rattling. It has been proposed to provide springs between the sash and pillar-molding; but such construction is objectionable, because, first, the spring is apt to wear the paint off the pillar-molding and 30 in all probability wear a groove therein, and, second, the sash is not permitted to move with sufficient ease. In other cases a spring carrying a metal roller has been secured to the upper or lower corner of the sash and 35 adapted to bear on the window-frame in a line parallel with the horizontal axis of the window-sash. Such construction might prevent the vibration of the window-sash in line with its horizontal axis or sidewise, but will 40 not effectually prevent the vibration of the sash at right angles to its horizontal or longitudinal axis.

It is the object of my present invention to obviate the numerous objections of prior 45 constructions and to so construct a window-sash that rattling thereof shall be prevented.

A further object is to provide a window-sash with devices whereby the sash shall have free vertical movement.

50 A further object is to provide a window-

sash with a series of anti-friction rollers and to so arrange the same that the sash itself will be prevented from coming into direct contact with the window-frame or pillar-molding on either face or bottom.

55

A further object is to so construct and arrange the devices that the nails or similar devices usually placed in the window-sill for the reception of the sash will be dispensed with.

60

A further object is to provide window-sash attachments which shall be simple in construction, effective in operation, and by means of which the manipulation of the sash is rendered easy.

65

With these objects in view my invention consists in certain novel features of construction and peculiar combinations and arrangements of parts, as hereinafter set forth, and pointed out in the claims.

70

In the accompanying drawings, Figure 1 is a view of a portion of a window-sash having my improvements applied thereto. Fig. 2 is an edge view of a sash having my improved devices affixed thereto. Fig. 3 is a view of 75 the blank for forming the box which contains the spring-sustained arm, said arm being shown in position. Figs. 4 and 5 are views of modifications.

75

A represents a window-sash having a recess *a* in each upper corner for the reception of boxes *B*, which latter are secured in place by means of screws or otherwise. Each box is made from a sheet-metal blank, as shown in Fig. 3, having spacing blocks or collars *b* 85 inserted between the side walls thereof near each end, by means of which the sides of the box are maintained in proper position. The side walls of the box are provided with perforations for the reception of screws, which 90 pass through the collars *b* and into the sash to secure the device thereto. An arbor *c* is fixed in the box *B* near the lower end thereof and serves as the fulcrum for an arm or lever *C*. The arm or lever *C* preferably comprises 95 two side plates *d*, held together by pins *e* *e'* *e''*, which pass from one to the other. Near its lower extremity the plates *d* are provided with perforations for the reception of the arbor *c*. A spring *D* is loosely coiled at its cen- 100

ter about the pin e , bearing at one end against the rear wall of the box and at the other end against the pin e' . The spring forces the free end of the arm C outwardly, as shown in the drawings, such outward projection of the arm being limited by two small projections f , which project inwardly from the side walls of the box, and which may be readily produced by indenting the material of which the box is made with a suitable tool. Mounted on the pin or arbor e^2 , at the free end of the arm C , is a roller E . This roller is preferably made with a central metallic portion and a rim g of rubber, the under face of said rim, where it rests on the body of the roller, being made with a flat bearing-face, while the exposed side of the strip is preferably made convex.

It will be seen that when the sash is in position in the frame the roller E will bear upon the pillar-molding of the frame with a pressure equal to the force of the spring D , and that when the sash is raised or lowered the contact of the rubber rim of the roller with the pillar-molding will not mar the same.

25 An elongated slot F is made near the lower end of the rear face of the box B for the accommodation of a rubber-rimmed roller E' , which projects through the slot and bears on the pillar-molding opposite the portion on which the roller E bears. The roller E' is mounted and adapted to rotate on the arbor c , on which the arm C is mounted. Thus it will be seen that the rollers E E' are mounted to rotate at right angles to the longitudinal axis 35 of the sash, and that as the roller E bears against the pillar-molding with a pressure equal to the force of the spring D , the roller E' is made to bear against the opposite portion of the pillar-molding, and vibration or 40 rattling of the sash is effectually prevented.

A recess h is made in the lower corner of each upright of the sash, over which projects a plate h' , secured at its upper end to the sash and provided at its lower end with a perforation. A pin or arbor h^2 passes across the recess h , being held at one end by a plate h' and at the other end by the sash upright. A roller i , preferably having its periphery covered with rubber, is mounted upon the shaft 45 or arbor h^2 , and is of sufficient size to permit its periphery to protrude beyond both side faces and bottom edge of the sash upright, so that when the frame is moving up or down the lower end thereof will not come into direct contact with the window-frame, and so 55 that when the sash is in its lowermost position it will rest upon the rollers i .

In another form of my invention each box B is made from a sheet-metal blank, as shown in Fig. 4, having small blocks b' b^2 inserted between the side walls thereof, which blocks produce the ends of the box and maintain the side walls in proper position. The lower block b^2 is provided on its upper ends with 60 V -shaped notch c' , and slightly above this notch the side walls of box B are provided

with aligned perforations for the reception of a pivot-pin c^2 . Mounted on the pin c^2 is an arm C' , the square corner at the lower end of which is adapted to pass into the notch c' , and thus permit said arm to be turned on its pivot. The arm C' is preferably made in a single piece of sheet metal bent in the form of an oblong box open at one edge and cut away at its top to produce ears 75 d' . A roller E is pivoted between the ears d' and adapted to bear against a portion of the pillar-molding of the window-frame, being maintained in firm contact with said molding by means of a spring E^2 . This spring is preferably made of a single piece of steel wire coiled at its center loosely around the pivot-pin c^2 , one of its free ends bearing on the box B , and its other end bearing on the arm C' . The box B is furnished near its upper end 80 with an elongated slot c^4 for the accommodation of a portion of the periphery of a roller f' , journaled in the side walls of the box.

In another form of my invention (shown in Fig. 5) the blocks b' b^2 are dispensed with and an ear j projects at the upper end of the box, by which to secure the device to the sash. As shown in Fig. 5, the lower end of the arm C may be rounded, and a spring k secured at one end to said arm, its other end being coiled upon and secured to the pivot-pin c' .

Having fully described my invention, what I claim as new, and desire to secure by Letters Patent, is—

1. The combination, with a window-sash, of a box having a slot near one end, a roller mounted in the box and adapted to project through said slot, a spring-sustained arm pivoted in the box and projecting from the opposite edge thereof, and a roller mounted in the free end of said arm, substantially as set forth.

2. The combination, with a window-sash, of a box secured thereto, a spring-sustained arm pivoted in said box, a roller journaled in the free end of said arm, and a roller journaled in each lower corner of the sash, the peripheries of said rollers protruding beyond both side faces and bottom edge of the sash, substantially as set forth.

3. The combination, with a window-sash, of a box secured in each upper corner thereof, an arm pivoted in each box, a roller carried by said arms, and a spring coiled about the pivot-pins of each arm, said springs bearing at one end against the arms and at the other end against the boxes, substantially as set forth.

4. The combination, with a window-sash, of a box secured in each upper corner thereof, an arm pivoted in each box, each of said arms being made of a single piece of sheet metal, rollers carried by said arms, and springs for maintaining said arms in a normal outward position, substantially as set forth.

5. The combination, with a sash, of a box,

a pin secured thereto, a roller mounted on said pin, and a spring-actuated arm also mounted on said pin and carrying a roller at its free end, both of said rollers adapted to bear on the pillar-molding, substantially as set forth.

In testimony whereof I have signed this

specification in the presence of two subscribing witnesses.

F. HERMANN JURY.
